UNITED STATES PATENT OFFICE

133,442

DESIGN FOR A SHOE

Harry Le Roy Sutcliffe, New York, N. Y.

Application July 10, 1942, Serial No. 107,470

Term of patent 3½ years

To all whom it may concern:

Be it known that I, Harry Le Roy Sutcliffe, a citizen of the United States of America, residing in New York city, county of New York, and State of New York, have invented a new, original, and ornamental Design for a Shoe, of which the following is a specification, reference being had to the accompanying drawing, forming part thereof.

Fig. 1 is a front perspective view of a shoe showing my new design.

Fig. 2 is a perspective view of the opposite side thereof.

The dominant feature of my design resides in the portions shown in solid lines.

I claim:

The ornamental design for a shoe, substantially as shown and described.

HARRY LE ROY SUTCLIFFE.
